ALFRED L. HARDING, OF BRANSON, MISSOURI, ASSIGNOR OF ONE-THIRD TO LEE MOORE,
OF BRANSON, MISSOURI

ROTARY VALVE FOR INTERNAL COMBUSTION ENGINES

Application filed May 15, 1929. Serial No. 363,259.

The present invention is directed to improvements in rotary valves for internal combustion engines.

The primary object of the invention is to provide a device of this character so constructed that the admission of explosive gases to the cylinder and the discharge of burnt gases therefrom can be controlled in a simple and practical manner.

10 Another object of the invention is to provide a valve of this type so constructed that wear thereof is reduced to a minimum.

Another object of the invention is to provide a valve of this kind wherein the burnt 15 gases will be completely exhausted so as to permit a clean explosive mixture to enter the valve casing.

Another object of the invention is to provide a valve of this kind so constructed that 20 the collection of carbon will have no detrimental effect but will serve to effectively seal the valve for more effective operation.

With these and other objects in view, this 25 invention resides in the novel features of construction, formation, combination and arrangement of parts to be hereinafter more fully described, claimed and illustrated in the accompanying drawings, in which:

Figure 1 is a vertical sectional view through 30 a portion of a cylinder and its associated valve casing, showing the relative arrangement of the valve and cooperating parts.

Figure 2 is a plan view of the valve seat.

Figure 3 is a bottom plan view of the 35 valve.

Figure 4 is a developed sectional view on the line 4-4 of Figure 3.

Figure 5 is a sectional view on the line 5-5 of Figure 1.

40 Figure 6 is a sectional view on the line 6-6 of Figure 1.

Fig. 7 is a radial section of Fig. 2 from the center of the valve showing the connection between the port and the space above 45 the valve, which are indicated by dotted lines in Fig. 1.

Referring to the drawings, 1 designates a portion of a cylinder in which reciprocates the usual piston 2, there being a passage 3 50 which communicates with the valve casing 4,

and since the head 5 is removable, access can be conveniently had to the casing to make adjustments and replacements when necessary. The casing is preferably cast integral with the cylinder and is provided with a bearing 6 and seat 7, said seat having an annular wall 8 formed thereon to provide an annular groove 9. The seat is further provided with an oil channel 10 which is furnished with oil through the passage 11 formed in the casing in order that a film of oil may be present between the seat and valve 12, the superfluous oil draining through the passage 12' into the oil pan. The valve 12 is in the nature of a disc and has a neck or stem 13 for rotatably engaging the bearing 6. The lower end of the stem is provided with an extension 14 for detachably engaging the socket 15 formed in the collar 16 rotatable with the driving gear 17 operable in the usual manner by the timing gear, not shown, to impart rotary movement to the valve 12. A spring 18 encircles the stem 13 and has its upper end bearing against the lower face of the casing 4, the lower end of said spring being seated upon a ball bearing assembly 19 upon the stem, said assembly being retained in place by the split washer 20. This spring will obviously hold the valve 12 properly seated but will allow said valve to move slightly to accommodate expansion and retraction of the parts.

The seat 7 is provided with a groove 21 which serves to return the surplus oil to the groove 10 for discharge into the oil pan 80 through the passage 12'.

The seat 7 has opening thereinto a main inlet port 22 and an auxiliary inlet port 23 and a main exhaust port 24 and an auxiliary exhaust port 25. The valve 12 has formed therein a single opening 26 and is formed in its under surface with a by-pass 27 which operates with the respective inlet and exhaust ports during rotation of the valve.

In Figure 4, the ports 24 and 25 are in registration with the opening 26 and by-pass 27, at which time the engine is exhausting. Obviously, the exhaust gases will pass over the valve 12, through the opening 26 and by-pass 27 and through the ports 25 and 24 which 95 100

discharge into any well known type of manifold, not shown. On the intake stroke of the piston, the valve will rotate so as to cause registration of the opening 26 and by-pass 27. 5 The function of the by-pass 27 will be more clearly understood by again referring to Figure 4 and Figure 1. While the port 26 is the only port cut completely through the valve and ordinarily its area would be the effective 10 area of the outlet and inlet of gases at all times, it will be seen that when the port 26 is passing out of register with the port 24, the by-pass 27 is beginning to register with the port 24 and the flow of gases from the space 15 3 is beginning to diminish through the opening 26, the flow is beginning to increase through the auxiliary port 25 which opens laterally into the space as shown in Figure 1, and this flow progressively increases as the 20 flow through the port 26 diminishes until the time when the by-pass 27 passes out of register with the auxiliary port 25. Thus, it is clear that the by-pass 27 permits of a longer period through which the exhaust port 24 in 25 the valve seat is open or in communication with the space 3. On the exhaust stroke this permits of a more thorough purging of the burnt gases from the cylinder. On the intake stroke the by-pass 27 likewise permits of 30 a longer period during which the space 3 is in communication with the inlet port 22 than would be the case were the single port 26 used without the by-pass as will be understood.

25 By providing the auxiliary port 25 and by-pass 27, the port area will be more effective during the time it is open to reduce back pressure to a minimum.

Since carbon will collect in the groove 9, 40 the valve will be sealed thereby and will operate more effectively.

Owing to the increased port area of the exhaust ports the burnt gases will be quickly dispelled so as to in no way interfere with the 45 incoming explosive charge upon the down stroke of the piston 2.

What is claimed is:

1. The combination with an internal combustion engine cylinder, of a casing carried 50 thereby and communicating therewith, said casing having a seat therein, a valve rotatably mounted on the seat, means for rotating the valve, said casing having main inlet and exhaust ports and auxiliary inlet and exhaust ports, said valve having an opening 55 therein communicating with a bypass, said opening and bypass being adapted to successively register with the respective inlet and exhaust ports during rotation of the valve.

60 2. The combination with an internal combustion engine cylinder, of a valve casing carried thereby and having communication with the cylinder, said casing having a bearing 65 therein, a seat in the casing, a valve having a stem engaging the bearing, said valve being

rotatably engaged upon the seat, means for rotating the valve, said casing having a main inlet and an auxiliary inlet passage opening thereinto, and a main exhaust and auxiliary port opening thereinto, said valve having an 70 opening formed therethrough and communicating with a bypass, said opening and bypass being adapted to successively coincide with the respective inlet and exhaust ports.

In testimony whereof I affix my signature. 75
ALFRED L. HARDING. [L. S.]
